UNITED STATES PATENT OFFICE.

LEONARD L. CONKEY, OF BENTON HARBOR, MICHIGAN.

BUCKLE.

SPECIFICATION forming part of Letters Patent No. 395,742, dated January 8, 1889.

Application filed November 14, 1888. Serial No. 290,768. (No model.)

To all whom it may concern:

Be it known that I, LEONARD L. CONKEY, a citizen of the United States, residing at Benton Harbor, in the county of Berrien and State 5 of Michigan, have invented a new and useful Improvement in Buckles, of which the following is a specification.

The above-mentioned device is designed to form a buckle for a chain, rope, strap, cable, 10 or other strand or thong which will admit of the chain, rope, cable, or other strand being passed through in one direction, but will prevent the same from passing in an opposite direction.

15 A further and fuller description of the device is as follows, reference being had to the accompanying drawings, making part of this specification, in which—

Figure 1 is a view of the buckle with the 20 strand held in place. Fig. 2 is a sectional view with a part of the hinge removed to show the working of the coiled metallic spring which facilitates the working of the buckle-tongue.

25 Like letters refer to like parts in both views.

In the drawings, A represents the jaws or frame of the buckle.

B represents the hinge, on which the tongue 30 turns.

C is the tongue, which is somewhat longer than the space between the hinge B and the front e of the jaws or frame A, which tongue is formed with a slot, c, in its outer end.

35 D is a coiled metallic spring within the hinge B, and which spring has the end f at-

tached to the jaws or frame A and the end g attached to the tongue C.

The purpose of the invention is to prevent any backward slipping of the chain, rope, cable, or other strand or thong that is being passed through, and the practical working is as follows: The chain or other strand is passed upward, as in Fig. 1, when the tongue C will be lifted from the frame or jaws A by turning on the hinge B, allowing the strand to pass freely so long as it is forced forward; but should the force be exerted backward or in the opposite direction the tongue C, aided by the coiled metallic spring D, will descend 50 against the front e of the jaws or frame A, and the strand will be forced into the slot c of the tongue C and its movement in that direction entirely stopped.

What I claim as my invention, and desire 55 to secure by Letters Patent, is—

A buckle comprising, in combination, a frame or jaws, A, a tongue, C, the outer end of which is provided with a slot, c, which tongue C works upon a hinge, B, together with 60 a coiled metallic spring, D, within the hinge B, attached to the frame or jaws A and the tongue C, so that the tension will incline to keep the outer end of the tongue C against the outer end of the jaws or frame A, substan- 65 tially as described.

In testimony whereof I affix my signature in presence of two witnesses.

LEONARD L. CONKEY.
